UNITED STATES PATENT OFFICE

ADOLPH MUELLER, OF DECATUR, ILLINOIS, ASSIGNOR TO H. MUELLER MFG. CO., OF DECATUR, ILLINOIS, A CORPORATION OF ILLINOIS.

INTERCHANGEABLE SELF-CLOSING AND COMPRESSION COCK.

1,087,543.

Specification of Letters Patent.

Patented Feb. 17, 1914.

Application filed October 1, 1910. Serial No. 584,934.

To all whom it may concern:

Be it known that I, ADOLPH MUELLER, a citizen of the United States, residing at Decatur, in the county of Macon and State of Illinois, have invented new and useful Improvements in Interchangeable Self-Closing and Compression Cocks, of which the following is a specification.

My invention consists of an interchangeable self-closing and compression cock, which may be used either as a self-closing or a compression cock by the simple change of one or more operating parts. Such a cock is of considerable advantage both to dealers, and the trade, for there are many situations in which it is desirable that a self-closing cock be used as a compression cock, and vice-versa. Among these situations may be mentioned one when a close regulation of flow is desired, and a self-closing cock is being used. By my invention the self-closing cock can be readily changed to a compression cock. In another of these situations it is found that when there is a small amount of leakage through a self-closing cock this leakage can be stopped by a compression of the valve slightly greater than can be had by the usual spring in the self-closing cock. Where the pressure on a main with which are connected self-closing cocks having a given closing pressure, is raised, another use for my invention is found, a simple conversion of the cock from a self-closing cock into a compression cock, serving the purpose. Still another situation in which my invention finds advantageous use is that in which a continuous flow, regulated in amount, is desired. And besides these situations, which arise, mainly, after the valve or cock is in use, a dealer by keeping these valves in stock, materially lessens the amount of stock which it is necessary for him to keep on hand, for he may sell the same valve either as a compression, or a self-closing cock.

In the accomplishment of my invention I have provided for use in connection with a single main body casing, which casing is formed with special reference for use in connection with one form of cock, either self-closing or compression, interchangeable operating means. One of these operating means is adapted to operate the cock as a compression cock, while the other is adapted to operate the cock as a self-closing cock. Preferably I form one of these operating

means, as well as the main body casing, of standard dimensions, and of the usual type. The other of the operating means I accommodate to the main body of the casing.

In the accompanying drawings I have shown one embodiment of my invention in which a compression cock operating means is accommodated to be used with the main body casing of a self-closing cock.

Of the drawings:—Figure 1 shows an assembled self-closing cock, and Fig. 2 shows a compression cock operating means of my invention applied to the main body casing.

10 is the main body casing of the valve. 11 is the valve seat, and 12 is a screw-threaded bore to the exterior of the casing, located directly above the valve seat.

Referring first to Fig. 1 13 is the valve, 14 the stem by which it is carried, 15 the closing spring, 16 the adjusting nut engaging the internal screw-threads of the bore 12, 17 the gland nut, 18 the lower trackway carried by the upper end of the gland unit, 19 the handle, 20 the upper trackway formed on the under side of this handle, 21 the intervening rollers between the engaging surfaces, and 22 the cap nut or abutment against which the handle bears. These are the usual parts of an operating means of a standard self-closing cock of a well known type.

According to my invention, I provide a supporting means for a compression cock operating means, adapted to be secured to the main body 10 of the casing of the self-closing cock shown in Figs. 1 and 2. The form of compression cock operating means shown in Fig. 2 consists of a supporting sleeve 23, of an external diameter adapting it to fit within the screw-threaded bore 12 as shown. This sleeve is provided interiorly with compression screw-threads 24, and exteriorly with a projecting flange 25 near its upper end. This sleeve 23 supports the operating stem 26, which is provided with engaging compression screw-threads 27, and which in turn carries the valve 28 on its lower end, and the operating handle 29 on its upper end.

It is to be noted that the operating handle 105 is provided with a squared socket to fit the squared end of the stem, and is held in place by a cap nut 30. This compression cock operating means is held in place on and within the casing 10 by a gland nut 31 which 110

clamps the upper flange 25 of the supporting sleeve 23 to the upper end of the main casing as shown. The upper end of the gland nut 31 is reduced in section similar to the gland nut of the self-closing operating means, and the handle is provided with a bonnet which covers its upper reduced end. The upper reduced end is dished at 32, in order to give greater play for the socketed portion 33 of the handle.

Thus it should be evident that I have attained all the objects of my invention, and produced an interchangeable compression and self-closing cock, in which all the advantages claimed are realized.

Among the advantages not mentioned may be noted that accruing when it is desired to change from a self-closing to a compression cock, as the connection of the shank of the valve casing with the supply pipe is difficult to make or is difficult or impracticable to reach. In that case the self-closing operating means is removed and the compression cock operating means substituted; whereupon the self-closing cock becomes a compression cock, and operates with all the efficiency of the standard compression cock.

A prime advantage derived from my invention is that it meets with the demand of hotel and public resort keepers for an interchangeable self-closing and compression cock. By using my invention, a hotel plumber can change a self-closing cock to a compression cock in an incredibly short time and since some people want a steady flow of water, while others want a limited flow, the varied desire of patrons is easily met.

While I have described the best form of my invention known to me, it should be obvious that my invention may be given several forms without departing in anywise from its generic spirit, and all of these forms I therefore desire to cover in the annexed claims.

What I claim is:

1. In combination with a valve casing constructed to receive the associate parts of a self-closing cock, means for converting the self closing cock to a manually operated cock, said means comprising a sleeve for in-

sertion in the valve casing, a gland nut carried on the casing for binding the sleeve therein and being reduced and dished out at its upper end, compression operating means in the sleeve having a stem projecting up through the gland nut, and a handle on the upper end of the stem provided with a bonnet overlapping the upper reduced end of the gland nut to house the stem at all adjustments of the manually operated valve.

2. In combination with a valve casing constructed to receive the associate parts of a self-closing cock, convertible means for the cock to adapt it for manual closing, said means comprising a sleeve for insertion in the valve casing, compression operating means carried by the sleeve, a gland nut carried by the casing for binding the sleeve therein, and a handle associated with the operating means and having a bonnet inclosing the upper end of the gland nut whereby to house said operating means.

3. In combination with a valve casing having a stem therein provided with a valve, a handle on the valve stem having an inclined trackway in its underside, a detachable gland nut on the casing supporting said stem and provided with an inclined trackway on its upper end, rollers interposed between the trackways, and a spring normally urging the trackways together whereby to close said valve automatically, means for converting said automatically closing cock to a manually operable cock, said means comprising a threaded stem provided with a valve, a threaded sleeve for insertion in the casing and engaging in threaded relation with said stem, a gland nut carried on the casing adapted to hold said sleeve in the casing, and a handle on the stem for turning the same and being provided with a bonnet adapted to close the upper end of the gland nut.

In testimony whereof I have hereunto set my hand in presence of two subscribing witnesses.

ADOLPH MUELLER.
